Filed Feb. 17, 1958, Ser. No. 715,741

5 Claims. (Cl. 312—311)

This invention relates, in general, to a new and improved dispenser of draft beer and the like, and in particular, to a new and improved cabinet or closure for enclosing a keg or barrel of beer beneath a beer tap, which closure forms part of a conventional bar of a tavern, cocktail lounge, and the like.

Heretofore, in taverns and the like, where draft beer is dispensed, it is common practice to directly draw or tap a keg or barrel of beer located in a cabinet immediately beneath the counter top of the bar. Such cabinets have had hinged doors and the barrel, being relatively heavy, has heretofore been awkward to handle. Because the hinged doors opened outwardly, the passageway or aisle behind the counter became clogged when the doors were opened; and because no provision has been made for conveniently inserting the keg into the cabinet, sliding doors have heretofore been unsuitable; sliding doors usually requiring tracks or the like which become damaged during the insertion and removal of the keg.

Accordingly, another general object of my invention is the improvement in prior type cabinets whereby the space near the cabinet is not clogged by the doors when access thereto is desired and whereby heavy objects may be conveniently inserted in, and removed from, the cabinet.

Still another specific object of my invention is to improve prior art cabinets utilized as part of bars in taverns and the like, by utilizing sliding doors and a convenient means of inserting a keg or barrel within the cabinet without damage to the tracks of the sliding doors.

I propose to accomplish these general and specific objects by the provision of sliding doors in a cabinet and a roller mounted sliding rack capable of being moved partially outwardly from the cabinet. My sliding rack is so constructed and arranged to permit the easy insertion and removal of a keg or the like to and from the sliding rack, and means are provided outwardly of the cabinet which prevents the door tracks from being damaged when the rack is being used.

Accordingly, a more specific object of my invention is the provision of a sliding rack in a beer dispensing cabinet having sliding doors and means for preventing the damage of the tracks of the sliding doors when the sliding rack is utilized.

An additional important feature of my invention is the construction and arrangement of the sliding rack whereby a dolly or hand-truck may easily bring a keg or barrel for direct placement on, or remove the keg from, the rack when the rack is in its outwardly extending position.

Still another feature of my invention is the provision of a means in the form of an air baffle plate located above the keg when in the cabinet and so constructed and arranged to cooperate with a fan in the cabinet for directing the cool air throughout the entire length of the line from the keg to the tap.

Other and more particular objects of my invention will be apparent to those skilled in the art from the

2

following description and drawings forming a part hereof and wherein:

Fig. 1 is a perspective view of a cabinet constructed in accordance with the teachings of my invention and illustrating the slide out rack conveniently receiving a keg for insertion in the cabinet;

Fig. 2 is a perspective view of the cabinet shown in Fig. 1 with the keg enclosed within the cabinet; and

Fig. 3 is a side, elevational, sectional view illustrating 10 to advantage the inner parts of my closure.

Turning now to the drawings, there is illustrated my new and improved closure or cabinet (shown fragmentarily), for dispensing draft beer and the like, indicated in its entirety as 10, forming part of a counter or bar-

15 top 11 (also shown fragmentarily) and having a conventional spigot or tap 12 from which beer or the like is dispensed and a conventional water spigot or tap 13 from which water is dispensed in a known manner. Suitable and conventional drain trays 14 and drains 15 (Fig. 3), as well as combination instruments 16 indicating the carbonation pressure and keg temperature, are provided; temperature instrument 16' being connected to a thermal responsive coil 17 located within the closure as illustrated in Fig. 3.

25 The closure, being generally of a conventional type, is provided with an insulated top 18, side and back walls 19 and 20, respectively, an inclined bottom wall 21; the latter being further provided with suitable and conventional draining means 22 for the drainage of water and 30 the like from the perspiring walls, water coils 23 for cooling the water for tap 13 and the refrigeration coils 24.

As hereinbefore mentioned, an outstanding feature of my invention is the provision of means permitting the utilization of sliding doors in a beer dispensing closure

35 of this type which have heretofore been unsuitable because of the damage likely to occur through the insertion and removal of a conventional pressurized container, such as a beer keg or barrel from the enclosure. Thus, to conveniently accomplish the utilization of sliding doors

40 25 and 26, I have provided suitable upper tracks 27 and lower tracks 28 upon which the sliding doors operate in a conventional manner and have provided a new and improved slide out rack, indicated in its entirety as 30, and comprising a lower, substantially rectangular, reinforced

45 floor 31, made of wire or the like of suitable stiffness and rigidity to support a barrel or keg 32, from which is upwardly extended a U-shaped wire rack or frame 33 opening outwardly and of the same general dimension as the lower end of the barrel or keg.

50 As illustrated in Figs. 1 and 2, to permit the easy access of a hand truck or dolly to insert the barrel 32 on the slide out rack 30, I have formed a cut-away portion 34 whereby the barrel may be precisely placed on the rack 30. It is to be noted that the slide out rack 30

55 is mounted on a plurality of rollers 35 suitably horizontally mounted on a U-shaped cabinet rack 36 made of angle irons or the like and permanently affixed to the sides and bottom of the closure 10 as illustrated. As illustrated, cabinet rack 36 is wholly within the cabinet

60 10 and the upper flange 37 is arranged to prevent tipping of the slide out rack when extended.

To prevent damage of the rack when loaded with the heavy keg 32 and to further prevent damage to the lower door tracks 28, still another roller 38 coated with rubber

65 or the like is mounted outwardly of the outer end of the closure 10 and tracks 28 as more clearly illustrated in Fig. 3. This roller 38 is so constructed and arranged to be of the same height as the rollers 35 and is, in this embodiment, substantially within a cover or the like 39.

70 Cover 39 permits the roller 38 to function, as illustrated particularly in Fig. 3, by being open at the top, yet covers the roller so as to prevent dirt and the like

from accumulating on the roller and to prevent damage to the roller itself during use.

From the above description, it can be seen that a dolly, such as illustrated in Fig. 1, may precisely position the barrel or keg 32 on the rack 30 when in extended or outward position and the barrel may be slidably received within the closure, through operation of the rack 30, as illustrated in Fig. 2; roller 38 functioning to prevent damage to the track 28 during this operation. When the barrel 32 is so located, as illustrated in Fig. 2 and Fig. 3, the same may be connected to the spigot 12 by flexible line 40 in the conventional manner.

As hereinbefore mentioned, still another important feature of my invention is the provision of a means functioning to cool the entire line from the keg 32 to and through the tap or spigot 12. This latter function is accomplished, in the embodiment disclosed, by a baffle plate 41 angularly disposed with respect to the refrigeration coils 24 and to the spigot whereby air from the refrigeration coils 24 may be directed upwardly the full length of the line 40 to the spigot. A fan 42 is located behind the coil 24 to direct the air across to the baffle plate where it is deflected upwardly through a relatively large hole 43 in the top 11 and out relatively small holes 44 on top of the spigot (Fig. 2). In this embodiment, the baffle plate 41 may be apertured to permit the line 40 to be extended therethrough if necessary or desirable and it is to be noted that the baffle plate is relatively narrow so as not to prevent the fan from directing air to cooling coils 23.

While I have described my closure in connection with one keg and one slide out rack, obviously, more than one slide out rack, such as illustrated at 31' may be used in conjunction with more than one keg and sliding doors and where herein the various parts of my invention have been referred to as located in a right or left or an upper or lower or an inward or outward position, it will be understood that this is done solely for the purpose of facilitating description and that such references relate only to the relative positions of the parts as shown in the drawings.

Also, it is to be understood that many changes and modifications may be made without departing from the scope or spirit of the invention and the invention is defined and comprehended solely by the appended claims which should be construed as broadly as the prior art will permit.

I claim:

1. A beverage dispenser comprising a cabinet for enclosing a beverage container, said cabinet having an access opening in a vertical rear wall thereof through which the beverage container is adapted to be moved into and out of said cabinet, sliding door means, and means including lower track means extending lengthwise of said rear wall at the bottom of said access opening for mounting said sliding door means for movement in the vertical plane of said access opening to open and close the same, a rack for supporting the beverage container, means within said cabinet for mounting said rack for sliding movement inwardly and outwardly of said cabinet in a horizontal plane at the lower end of said access opening and above said lower track means, and roller means below said access opening mounted for rotation on an axis extending lengthwise of and outwardly of said rear wall with its upper periphery lying in the plane of the bottom of said rack to support said rack above said lower track means when said rack is disposed in a position extending outwardly of said access opening.

2. A beverage dispenser comprising a cabinet for enclosing a beverage container, said cabinet having an access opening in a vertical rear wall thereof through which the beverage container is adapted to be moved into and out of said cabinet, sliding door means, and means including lower track means extending lengthwise of said

rear wall at the bottom of said access opening for mounting said sliding door means for movement in the vertical plane of said access opening to open and close the same, a rack for supporting the beverage container, means within said cabinet for mounting said rack for sliding movement inwardly and outwardly of said cabinet in a horizontal plane at the lower end of said access opening and above said lower track means, roller means below said access opening mounted for rotation on an axis extending lengthwise of and outwardly of said rear wall with its upper periphery lying in the plane of the bottom of said rack, and a cover mounted outwardly on said rear wall below said access opening for enclosing said roller means, said cover having an opening extending lengthwise along its upper end for exposing the upper periphery of said roller means for supporting said rack above said lower track means when said rack is disposed in a position extending outwardly of said access opening.

3. A beverage dispenser comprising a cabinet for enclosing a beverage container, said cabinet having an access opening in a vertical rear wall thereof through which the beverage container is adapted to be moved into and out of said cabinet, sliding door means, and means including lower track means extending lengthwise of said

25 rear wall at the bottom of said access opening for mounting said sliding door means for movement in the vertical plane of said access opening to open and close the same, a rack for supporting the beverage container, means within said cabinet for mounting said rack for sliding

30 movement inwardly and outwardly of said cabinet in a horizontal plane at the lower end of said access opening and above said lower track means, roller means below said access opening mounted for rotation on an axis extending lengthwise of and outwardly of said rear wall with its upper periphery lying in the plane of the bottom of said rack to support said rack above said lower track means when said rack is disposed in a position extending outwardly of said access opening, and frame means connected with and extending vertically upwardly and transversely rearwardly of the upper surface of said rack to define an abutment for locating the beverage container thereon, and said rack being unobstructed at the forward portion of its upper surface to facilitate the positioning of the beverage container thereon.

4. A beverage dispenser comprising a cabinet for enclosing a beverage container, said cabinet having an access opening in a vertical rear wall thereof through which the beverage container is adapted to be moved into and out of said cabinet, sliding door means, and means including lower track means extending lengthwise of said rear wall at the bottom of said access opening for mounting said sliding door means for movement in the vertical plane of said access opening to open and close the same, a rack for supporting the beverage container, means within said cabinet for mounting said rack for sliding

50 movement inwardly and outwardly of said cabinet in a horizontal plane at the lower end of said access opening and above said lower track means, roller means below said access opening mounted for rotation on an axis extending lengthwise of and outwardly of said rear wall with its upper periphery lying in the plane of the bottom of said rack to support said rack above said lower track means when said rack is disposed in a position extending outwardly of said access opening, and frame means connected with and extending vertically upwardly and transversely rearwardly of the upper surface of said rack to define an abutment for locating the beverage container thereon, and said rack having an opening

55 in the forward portion thereof through which the bottom of the beverage dispenser may be engaged and disengaged in positioning and removing the beverage container relative to said rack.

70 5. A beverage dispenser comprising a cabinet for enclosing a beverage container, said cabinet having an ac-

cess opening in a vertical rear wall thereof through which the beverage container is adapted to be moved into and out of said cabinet, sliding doors means, and means including lower track means extending lengthwise of said rear wall at the bottom of said access opening for mounting said sliding door means for movement in the vertical plane of said access opening to open and close the same, a rack for supporting the beverage container, means within said cabinet for mounting said rack for sliding movement inwardly and outwardly of said cabinet in a horizontal plane at the lower end of said access opening and above said lower track means, roller means below said access opening mounted for rotation on an axis extending lengthwise of and outwardly of said rear wall with its upper periphery lying in the plane of the bottom of said rack to support said rack above said lower track means when said rack is disposed in a position extending outwardly of said access opening, and vertically upwardly extending frame means for said rack extending along one side of said rack and transversely rearwardly thereof to define an abutment for locating the beverage container on said rack, and said rack having an opening extending inwardly of the front edge thereof forwardly and laterally

of said frame means through which the bottom of the beverage dispenser may be engaged and disengaged for positioning and removing the beverage container relative to rack when the latter is disposed in its outermost position relative to said access opening.
